UNITED STATES PATENT OFFICE.

JULIUS PEGEL, OF PHILADELPHIA, PENNSYLVANIA, ASSIGNOR TO JOHN BROMLEY & SONS, OF SAME PLACE.

DESIGN FOR A RUG.

SPECIFICATION forming part of Design No. 19,465, dated December 3, 1889.

Application filed November 7, 1889. Serial No. 329,588. Term of patent 3½ years.

To all whom it may concern:

Be it known that I, JULIUS PEGEL, a citizen of the United States, and a resident of Philadelphia, Pennsylvania, have invented a new and Improved Design for Rugs, reference being had to the accompanying photographic illustration, making part hereof, in which—

A is the ground-work of the rug; B, a middle oblong-square panel with scallops or fret-work along its inner edges; C, border-work around the panel B, consisting of flowers D, with radiating leaves and intermediate scrolls E at intervals; F, a diagonally-transverse bar across the panel, fretted on its edges.

G G are large flowers, generally resembling pond-lilies or sunflowers, within the panel B, on one side of bar F; and H H are leaves and ornamental work resembling leaves within the panel B, on the other side of bar F, as shown.

What I claim as new is—

The design for rugs, as shown.

In witness that the above is my invention I have hereunto set my hand.

JULIUS PEGEL.
